UNITED STATES PATENT OFFICE.

ADOLPH HIRSCH AND HENRY M. MARX, OF NEW YORK, N. Y.

DESIGN FOR ORNAMENTATION OF TEXTILE AND OTHER FABRICS.

SPECIFICATION forming part of Design No. 14,902, dated March 25, 1884.

Application filed January 19, 1884. Term of patent 7 years.

To all whom it may concern:

Be it known that we, ADOLPH HIRSCH and HENRY M. MARX, both citizens of the United States, residing at New York, in the county 5 and State of New York, have originated and produced a new Design for Ornamentation of Textile and other Fabrics, of which the following is a specification.

This design relates to embossed work which 10 is applicable to textile fabrics, leather, paper, or other material. The novel features are pointed out in the following specification, and illustrated in the accompanying drawings, in which—

15 Figure 1 represents a face view. Fig. 2 is a transverse section.

Similar letters indicate corresponding parts.

In the drawings, the letter A designates a piece of textile fabric or other material, which 20 is ornamented by a series of rows of panels, a, which are separated from each other by double ridges b b. Each panel bears a star, c,

and at the intersections of the ridges b b are ornaments d, each composed of four leaves and a center.

What we claim as new, and desire to secure 25 by Letters Patent, is—

1. The design for ornamentation of a fabric, consisting of the rows of panels a, the stars c in the panels, and the ridges b, separating the 30 rows of panels, substantially as shown and described.

2. The design for ornamentation of a fabric, consisting of the panels a, ridges b b, stars c, and ornaments d, substantially as shown and 35 described.

In testimony whereof we have hereunto set our hands and seals in presence of two subscribing witnesses.

ADOLPH HIRSCH. [L. S.]
HENRY M. MARX. [L. S.]

Witnesses:

W. HAUFF,
E. F. KASTENHUBER.
